UNITED STATES PATENT OFFICE.

LEON LUKACHER, OF CHICAGO, ILLINOIS.

COIN-WRAPPER.

1,134,687.

Specification of Letters Patent.

Patented Apr. 6, 1915.

Application filed June 17, 1914. Serial No. 845,569.

To all whom it may concern:

Be it known that I, LEON LUKACHER, a citizen of the United States, and a resident of the city of Chicago, county of Cook, and State of Illinois, have invented certain new and useful Improvements in Coin-Wrappers, of which the following is a specification.

My invention relates to improvements in coin wrappers and has for its object, the provision of means for facilitating the wrapping and marking of coins.

The invention consists in the combinations and arrangements of parts hereinafter described and claimed.

The invention will be best understood by reference to the accompanying drawing forming a part of this specification, and in which,

Figure 1 is a perspective view of an apparatus embodying my invention, and shown in one position of use, Fig. 2, a similar perspective view showing the apparatus in a different position for use, and Fig. 3, a perspective view of a stack of coins after being wrapped.

The preferred form of construction as illustrated in the drawing, comprises a coin holder 4 which is in the form of a sheet metal box open at the top and at its forward side so as to receive readily a stack of coins 5. One of the holders 4 is provided for each different kind of coins to be wrapped, the one illustrated being designed for use with half-dollars, and being of a size to receive snugly twenty half-dollars or a total of \$10.00 in currency. The holders for receiving coins of other denominations will be of lengths to serve as gages for measuring or counting the coins, the holder for nickels being adapted to receive snugly forty nickels, or a total of \$2.00 in currency, and the one for dimes, being of a size to receive fifty dimes, or \$5.00 in currency. Likewise, holders can be provided for coins of other denominations and the length thereof so limited as to serve as a gage or counter for the coins, as will be readily understood.

The ends of the holder 4 are provided with notches 6 adapted to receive the inwardly turned ends 7 of a pair of clamping tongs 8. The tongs 8 are formed of wire which are set well apart and have the ends 7 turned inwardly at right angles so as to permit of free rotation of a stack of coins 5 engaged by said ends. A stamp 9 is mounted on an arm 10 which is pivoted in a swivel-

block 11 at the pivot point of tongs 8 and is provided with a hook 12 engaging a spring 13 which has its other end secured to a U-shaped spring 14 serving to separate the handles 15 of the tongs.

In use, the stack of coins is arranged in the suitable holder and the ends thereof engaged by the ends of the tongs. This serves as a means for removing the stack of coins 65 which are then laid upon an ordinary paper coin wrapper 16 and said coin wrapper is then wrapped around the stack of coins, the stack of coins rotating between the ends 7 and said tongs being spread far enough 70 apart to permit the passage of the wrapper therebetween to facilitate this operation. The end of the coin wrapper is then sealed as usual, and the stamp 9 is depressed to contact with said wrapper and stamp the 75 name of the owner thereon. Then the stack is removed from the tongs and the ends of the wrapper folded inwardly over the ends of the stack thus completing the wrapper. Thus, it will be observed, that the coins may 80 be readily arranged in a stack of standard size and wrapped with great ease and rapidity.

While I have illustrated and described the preferred form of construction for carrying 85 my invention into effect, this is capable of variation and modification without departing from the spirit of the invention. I, therefore, do not wish to be limited to the precise details of construction set forth, but 90 desire to avail myself of such variations and modifications as come within the scope of the appended claims.

Having described my invention what I claim as new and desire to secure by Letters Patent is:

1. As a means for wrapping coins, a holder adapted to receive a stack of coins and adapted to permit of removal thereof, there being notches in the ends of said holder; and spring held tongs consisting of tong arms pivotally connected together and having inwardly turned ends adapted to be inserted through said notches to engage the ends of a stack of coins in said holder, substantially as described.

2. As a means for wrapping coins, a holder consisting of a sheet metal box open at the top and at the forward sides thereof so as to readily receive and permit the removal of a stack of coins, there being notches in the ends of said box; and spring held

wire tongs consisting of tong arms pivotally connected together and having inwardly turned ends adapted to be inserted through said notches to engage the ends of a stack of 5 coins in said holder, substantially as described.

In testimony whereof I have signed my

name to this specification in the presence of two subscribing witnesses.

LEON LUKACHER.
